UNITED STATES PATENT OFFICE.

WILLIAM J. TOY, OF OGDEN, UTAH.

WHEEL-FLANGE LUBRICATOR.

1,186,863.

Specification of Letters Patent. Patented June 13, 1916.

Application filed March 23, 1916. Serial No. 86,098.

To all whom it may concern:

Be it known that I, WILLIAM J. TOY, of Ogden, in the county of Weber and State of Utah, have invented a certain new and useful Improvement in Wheel-Flange Lubricators, of which improvement the following is a specification.

My invention relates to appliances for lubricating the wheel flanges of locomotive engines, in order to reduce the wear thereof and of the rails of the tracks over which they run, and its object is to provide a device of such type which shall be of simplified and inexpensive construction, ready applicability to locomotives of the various present standard types, and capability of freedom from obstruction of its operation by the action of low atmospheric temperatures.

The improvement claimed is hereinafter fully set forth.

In the accompanying drawings: Figure 1 is a diagrammatic side view, in elevation, of the forward portion of a locomotive engine, illustrating an application of my invention; Fig. 2, a transverse section, on the line $\alpha - \alpha$ of Fig. 1; Fig. 3, a longitudinal central section, on an enlarged scale, through a regulating valve casing, and, Fig. 4, a transverse section through a modified form of oil reservoir.

My invention is herein exemplified as applied for the lubrication of the flanges of the front pair of driving wheels of a locomotive, which in the instance shown is of a type having a four wheeled leading truck, a , a plurality or pairs of driving wheels, A , side frame members, B , B , of the usual "bar" form, and a boiler, C , the forward ring, C' , of which constitutes the ordinary smoke box, and is provided, at its top, with a stack, C^2 .

In the practice of my invention, I provide an oil reservoir, 1, which is preferably formed of a section of wrought iron pipe, 45 and is longitudinally bent to the curvature of the smoke box, C' , against one side of which it fits throughout its length, and to which it is detachably connected by clamps, 1^a , and bolts 1^b . The top of the reservoir, 50 through which it is supplied with oil, is closed by a removable screw cap, 1^c , having a small air admission perforation, and it is connected, at its lower end, by an elbow, 2^a , and T , 2^b , to a horizontal delivery pipe, 2, which extends across the locomotive, above the frame members, B , B . The pipe, 2, is

connected, at each of its ends, by an elbow, 2^c , to the casing, 3, of a regulating valve, 3^a , which is of the "needle" type and controls communication between the pipe, 2; and a discharge pipe, 4, having an outlet section, 4^a , leading from its lower end to a point adjacent to the flange of one of the front driving wheels. The discharge pipes are supported by clamps, 4^b , connected to the side frame members, in such downwardly and rearwardly inclined positions as will enable the free flow of oil to the flanges to be effected by gravity alone. The flow of oil from the reservoir to the outlet sections, 4^a , may be regulated as desired, by adjustment of the regulating valves, the stems, 3^b , of which are shouldered to form abutments for springs, 3^c , which tend to force the valves to their seats, and the valves are raised therefrom to the extent desired, by cams or handles, 3^d , on the stem, and held in adjusted position by lock nuts, 3^e , engaging threads, on bushings, 3^f , screwed into the valve casings.

In order to increase the extent of the surface of the oil reservoir which is exposed to the heat of the boiler, it may, if desired, be made of flattened transverse section, as shown in Fig. 4, instead of cylindrical section. It will, further, be obvious that the oil reservoir may, if preferred, be attached to, and fit against, a ring of the boiler shell proper, instead of being located, as shown in the drawings, on the smoke box ring thereof.

My invention attains the practical advantages of slight initial cost of application and practically none of maintenance; facility of supply and regulating of discharge of oil; and maintenance of the fluidity of the oil under the lowest atmospheric temperatures by the heat imparted to the reservoir by its contact with the boiler.

I claim as my invention and desire to secure by Letters Patent:

1. In a wheel flange lubricating appliance for locomotive engines, the combination of an oil reservoir, which is longitudinally curved to fit against the shell of a locomotive boiler; means for supporting said reservoir on the boiler; and means for effecting the gravity discharge of oil from the reservoir upon wheel flanges of the locomotive.

2. In a wheel flange lubricating appliance for locomotive engines, the combination of an oil reservoir which is longitudinally curved to fit against the shell of a locomotive

tive boiler; means for supporting said reservoir on the boiler; delivery means for conveying oil from the reservoir to opposite sides of the locomotive; and means for effecting the gravity discharge of oil from the delivery means upon wheel flanges of the locomotive.

3. In a wheel flange lubricating appliance for locomotive engines, the combination of 10 an oil reservoir which is longitudinally curved to fit against the shell of a locomotive boiler; means for supporting said reservoir on the boiler; means for effecting the gravity discharge of oil from the reservoir upon wheel flanges on opposite sides of the locomotive; and means for independently regulating each side discharge.

4. An oil reservoir for locomotive engine wheel flange lubricating appliances, which 15 is longitudinally curved to fit against the shell of a locomotive boiler and is provided

with a top supply opening closed by a removable cap, and adapted, at its lower end, for connection to an oil delivery pipe.

5. The combination, with a locomotive engine, of a longitudinally curved oil reservoir, fitted against the shell of the boiler; means for detachably connecting the reservoir to the boiler; a delivery pipe extending transversely below the boiler and communicating with the lower end of the oil reservoir; discharge pipes connected to the ends of the delivery pipe and leading to points adjacent to opposite wheel flanges; means for supporting the discharge pipes on the frame members of the locomotive; and means for regulating the flow of oil through the discharge pipes. 25 30 35
